WIRES DRAWING MECHANISM

Norman H. Nye, Cuyahoga Falls, Ohio, assignor to
 The Vaughn Machinery Company, Cuyahoga
 Falls, Ohio, a corporation of Ohio

Application November 18, 1939, Serial No. 305,115

10 Claims. (Cl. 205—20)

This invention relates, as indicated, to wire-drawing blocks and the like and more particularly to an improved method and apparatus for cooling such blocks and the wire wrapped thereon.

As wire is drawn through a die, it becomes highly heated and if the wire passes through successive dies without being cooled therebetween, such heating becomes excessive with resultant injury to the wire. This fact has long been recognized by those skilled in the art and various cooling means suggested to overcome the problem. That most generally accepted has been some form of water spray applied to the interior surface of the block or drum thus cooling both the drum and the wire wrapped thereon. Various disadvantages consequent upon the employment of this cooling means soon became apparent, however, such as the tendency of the water to enter the upper bearings supporting the block and the difficulty due to centrifugal force of removing the water from the block in the desired manner and at the desired rate.

It is, therefore, among the objects of this invention to provide an improved method and apparatus for cooling wire-drawing blocks.

Another object is to provide apparatus of the above-described type whereby the flow of a liquid cooling stream may be under positive control and contact with bearings and the like avoided.

A still further object is to provide a block in which both air and water are employed as cooling mediums.

Other objects of this invention will appear as the description proceeds.

To the accomplishment of the foregoing and related ends, said invention, then consists of the means hereinafter fully described and particularly pointed out in the claims.

The annexed drawings and the following description set forth in detail certain means and one mode of carrying out the invention, such disclosed means and mode illustrating, however, but one of various ways in which the principle of the invention may be used.

In said annexed drawings—

Fig. 1 is an elevational view in cross section of my new block showing a portion of the driving mechanism;

Fig. 2 is a vertical section along the line 2—2 on Fig. 3 of a take-up block or drum adapted for use in conjunction with a standard stripper and illustrating another embodiment of my invention;

Fig. 3 is a horizontal section taken along the line 3—3 on Fig. 2;

Fig. 4 is a horizontal section along the line 4—4 on Fig. 2;

Fig. 5 is a vertical section along the line 5—5 on Fig. 3; and

Fig. 6 is a vertical section along the line 6—6 on Fig. 3.

As indicated above, the principle of my invention is adaptable to the various types of wire-drawing blocks, drums and take-up reels commonly employed, whether they be single or double-decked, intermediate on a continuous bench, or the drum on which the wire is wound at the end of the operation. Broadly, the idea of cooling such blocks by means of water or air streams is old as taught by Pat. No. 1,723,313 to Tippet dated August 6, 1929, and Pat. No. 1,959,901 to McIlvried dated March 13, 1934.

Referring now more particularly to the above-identified drawings and especially Fig. 1, one preferred embodiment of my invention may comprise a cylindrical block or drum 1 about which the wire is wound, mounted on a tubular vertical spindle 2, said spindle being journaled at its lower end in roller bearing 3, and near its upper end in roller bearing 4. Bearing 4 is supported in supplemental frame 5 which, in turn, rests upon and covers the box-like main-frame 6. Said main-frame also serves as an oil reservoir in which the gears 7, 8 and 9, by which shaft 2 is driven, turn.

The wire-engaging surface of drum 1 is bounded above by flange 10 and below by sloping flange 11. Press-fitted or otherwise tightly secured within said drum is a complementary inverted cup-like member 12 with a rib 13 spiralling about its exterior which thus forms a spiral passageway 14 between the walls of said drum 1 and said member 12. Communicating with the upper end of said passageway is a centrally located chamber 15 in the bottom of which the upper end of tube 16 is journaled. Thus, member 15 rotates with drum or block 1 as a single unit about tube 16. Said tube is supported at its lower end by bracket 17 and connects with a water line 18 by way of valve 19.

Close fitted within the upper end of spindle 2 and turning with it is another tube 20, the upper end of which communicates with the interior of member 12 and the lower end of which debouches into chamber 21. From a point below where tube 20 is thus fitted to spindle 2, the bore of the latter is enlarged as shown, so as to

wire-winding block adapted to be water cooled comprising a cylindrical outer drum adapted to be mounted on a spindle, said drum being open at the top, a hollow cylindrical member inside said drum having a spiral rib about its exterior adapted to form a spiral passageway between said drum and said member when said member is fitted in said drum, and a liquid supply source communicating with such passageway.

6. In wire drawing mechanism, a take-up block adapted for use with coil stripping means comprising a hollow rotatable drum having radial recesses to accommodate the legs of such stripping means, such recesses dividing said block into a plurality of chambers, means for supplying a cooling liquid to one of said chambers, openings connecting said chambers, and means for the discharge of such liquid from another of said chambers.

7. In wire drawing mechanism, the combination of a vertical tubular spindle and a hollow rotatable take-up block mounted thereon adapted for use with coil stripping means, said block comprising a drum divided into a plurality of paired upper and lower chambers by radial recesses provided to accommodate the legs of such stripping means, a passageway within said spindle for introducing a cooling liquid to one of said chambers, passageways between such upper and lower chambers adjacent the wire-contacting portion of the block, openings connecting said pairs of chambers, and another passageway within said spindle communicating with another of said chambers to provide for the discharge of such liquid from said block.

8. In wire drawing mechanism, the combination of a vertical tubular spindle and a hollow rotatable take-up block mounted thereon, said

block comprising a drum composed of an upper and a lower section, radially disposed recesses in said drum provided to accommodate the legs and feet of a stripping mechanism and dividing said drum into a plurality of paired upper and lower chambers, passageways between such upper and lower chambers adjacent the wire-contacting portion of the block, a passageway within said spindle for introducing a cooling liquid to one of said chambers, openings connecting said pairs of chambers to provide for a continuous flow of such liquid through each of said chambers, and another passageway within said spindle communicating with the last chamber in the series to provide for the discharge of such liquid from said block.

9. In wire drawing mechanism, the combination of a tubular spindle, a hollow, rotatable, wire-winding block mounted thereon, a passageway within said block adapted to conduct a fluid cooling stream in a prescribed tortuous path traversing the interior surface of the wire-contacting portion of such block both axially and circumferentially, a passageway within said spindle for conducting the coolant to one end of said first-named passageway, and another passageway in said spindle to provide for the discharge of the coolant from the other end of said first-named passageway.

10. In wire drawing mechanism, a rotatable wire-winding block adapted to be water cooled, comprising a hollow rotatable drum divided into a plurality of chambers, means for supplying cooling liquid to one of said chambers, openings connecting said chambers in sequence, and means for the discharge of such liquid from the last chamber of the series.

NORMAN H. NYE.
